[57] ABSTRACT

A pressure regulator system for controlling pressure differential between a buoyancy sphere and the ambient water pressure during descent of the buoyancy sphere employs a control valve arrangement. The body of the valve arrangement is mounted integrally on the buoyancy sphere and communicates with the interior. A diaphragm control valve and pintle control the flow of gas producing fuel so as to regulate the amount of gas passing to the interior of the buoyancy sphere to thereby maintain a predetermined pressure differential. The valve mechanism also includes flushing means to cleanse portions of the interior of corrosive salt water and other materials admitted during operation.

DEPTH COMPENSATOR VALVE**STATEMENT OF GOVERNMENT INTEREST**

The invention described herein may be manufactured and used by or for the Government of the United States of America for governmental purposes without the payment of any royalties thereon or therefor.

FIELD OF THE INVENTION

This invention pertains to the field of naval architecture and marine engineering. More particularly, this invention pertains to the field of submersible marine engineering. Equipment to which the invention is directed is the buoyancy transport vehicle equipment used by untethered underwater divers. In still greater particularity, the invention pertains to a pressure regulation system to control the pressure differential between the buoyancy sphere portion of such buoyant transport vehicles and the ambient water pressure during descent of the buoyant transport vehicle.

DESCRIPTION OF THE PRIOR ART

For centuries, man has been interested in retrieving objects from the floor of the sea. In depths too great to be reached by surface probes and grappling means, divers have been the primary means for accomplishing these underwater retrieval tasks. Until comparatively modern times, the limitation on man's ability to recover such objects as he may desire from the floor of the ocean has been his ability to remain submerged for sufficiently long periods of time. Modern advances in diving suits, breathing systems, and other life support apparatus has greatly extended the length of time which man may remain below the surface. As in other arts, these modern advances have only highlighted further limitations on man's ability to control his new environment.

In particular, the primary motive power heretofore available to a worker employed beneath the surface of the water has been his own muscle power. In order to raise objects heavier than he has been able to lift and carry while swimming, man has had to depend upon a lifting arrangement controlled from the surface. Because of the difficulty in communication between the ocean floor and the surface as well as certain inherent engineering limitations concerned with the air water interface, these prior systems have left a great deal to be desired. Only by providing divers with mechanical, labor-saving lifting devices and similar aids for transporting heavy objects could the usefulness of the modern advances in diving be fully realized.

Recent innovations in this area included small salvage pontoons which may be placed on objects to be returned to the surface when inflated by the divers. However, the ultimate desire and recent realization has been the provision of a buoyant transport vehicle which could be regulated in buoyancy and propulsive forces by the diver to transport a load to a desired location in the ocean or on the ocean surface.

For the effective operation of such buoyant transport vehicles, a great many parameters must be effectively controlled. One such parameter which has given considerable trouble is the pressure exerted on the buoyant lifting chamber by submergence of the vehicle. In prior art arrangements, the pressure on the buoyancy sphere was manually controlled. As a result of divers becoming preoccupied with other tasks during submergence

or with inability to operate the controls in a proper sequence, damage to the buoyancy sphere was sometimes encountered. Of course, a certain amount of risk or danger to the divers also accompanies any damage or serious disruption of the integrity of the buoyancy sphere. These hazards are very undesirable and their minimization is, quite naturally, a goal of all engineering developments in this field.

For a variety of reasons, previous attempts to eliminate the manual operation of the pressure control for the buoyancy transport vehicle have been only marginally successful. Various regulator mechanisms have been tried but only with limited success. For example, scuba breathing regulators were tried to inject into the buoyancy sphere gas under high pressure so as to equalize the pressure differential during descent. However, a source of gas of sufficient size to fill the buoyancy chamber at great depths is impractical from a standpoint of size, as well as other considerations.

The most successful approach to the problem has been to generate the gas from a suitable fuel in a reaction chamber and inject the gas into the interior of the buoyancy sphere and thereby equalize the pressure. However, the regulation of the flow of fuel to the gas generator has caused problems similar to those mentioned above in connection with the introduction of gas under pressure from an external source. Known regulator valves to accomplish this purpose automatically have been mechanically too fragile for the arduous working conditions imposed in underwater applications. Also, the corrosive action and deposits carried by the seawater causes premature failure of valves of known manufacturing type.

STATEMENT OF THE OBJECTS OF THE INVENTION

Accordingly, it is an object of this invention to provide an improved buoyancy control system.

Another object of this invention is to provide an improved buoyancy control system utilizing a regulated flow of gas generating fuel.

A further object of this invention is to provide fuel regulation valve for a buoyancy chamber.

Yet another object of this invention is to provide a buoyancy control system employing a valve having high mechanical strength.

Another object of this invention is to provide a buoyancy control system employing an automatic valve having provisions for minimizing the corrosive effects of seawater.

Still another object of this invention is to provide a buoyancy control system incorporating a regulation valve which will regulate a gas producing fuel flow to a gas generator so as to alter the pressure within a buoyancy system.

Still another object of this invention is to provide an improved diaphragm type valve capable of withstanding the sustained operation beneath the surface of the sea.

These and other objects of the invention will become more readily apparent from the ensuing specification when taken with the drawings.

BRIEF DESCRIPTION OF THE DRAWINGS

FIG. 1 is a perspective view of a mobile transport vehicle employing the buoyancy control system of the invention;

FIG. 2 is an enlarged partial sectional view of the buoyancy sphere on the buoyancy transport vehicle of FIG. 1 showing the mounting of the buoyancy control valve according to the invention; and

FIG. 3 is a sectional view taken along lines 3—3 of FIG. 2.

DESCRIPTION OF THE PREFERRED EMBODIMENT

Referring to FIG. 1, the buoyancy transport vehicle, indicated generally at 11, is shown being operated by a diver-operator 12 moving an object 13. Object 13 is affixed to buoyancy transport vehicle 11 by means of suitable tackle and other conventional purchase, such as hook 14. The principal component of buoyancy transport vehicle 11 is a suitable buoyancy or lifting sphere 15. Buoyancy sphere 15 is surrounded by an appropriate framework 16 which protects the buoyancy sphere and other apparatus mounted on buoyancy transport vehicle 11 from contact with the sea bottom or other objects. The buoyancy transport vehicle 11 is moved by means of suitable propulsion units indicated generally at 17. In the embodiment shown, there are two horizontally aimed thruster units and two vertically aimed units. Of course, other combinations and arrangements of conventional propulsion means may be employed if desired. The control of the buoyancy transport vehicle 11 is effected by diver-operator 12 by means of a suitable control console 18. Any suitable control console arrangement may be used but that disclosed in the inventor's copending application Ser. No. 237,304 filed Mar. 23, 1972 for "Buoyancy Transport Vehicle Control Console," has proven successful.

As shown, framework 16 supports other equipment which forms part of the buoyancy transport vehicle. Of particular note is a lower pod 19 which contains a source of gas producing fuel. The particular fuel employed depends upon the type of gas generator employed and other parameters which may be varied to suit the particular application. However, for purposes of completeness and by way of explanation, it should be noted that hydrazine has been used successfully in the device of the invention. The hydrazine fuel supply is connected to the gas generator by suitable fluid conduit means 21. Referring to FIG. 2, a fragmental view of the buoyancy sphere 15 shows the arrangement by which the valve control system according to the invention is mounted thereon. As shown, the valve, indicated generally at 22, extends outwardly from the surface of buoyancy sphere 15. Of course, if desired, the exposed valve body 22 and adjacent conduit 21 may be enclosed by a suitable shielding box so as to protect it from accidental impact. As will become more clear subsequently, if such a protective cover is employed it must be free to communicate with the ambient pressure environment in which the buoyancy transport vehicle operates.

As shown, the valve 22 comprises two major portions. A valve body portion 23 is outermost in relation to buoyancy sphere 15. A housing portion 24 supports the valve body portion 23 and emerges from the interior of buoyancy sphere 15. Housing portion 24 may be secured to buoyancy sphere 15 by any of several suitable means. For example, the valve 22 may be integrally formed with sphere 15 or, as illustrated, be secured by a plurality of threaded fasteners 25.

After passing through the depth compensator valve, the hydrazine fuel goes through a check valve, not shown, and then into a suitable gas generator 26 where the fuel is discomposed to form hot gases. These gases pass through a heat exchanger, not shown, and another check valve, not shown, before being injected into buoyancy sphere 15. The gas generator may be one of several available types and, if desired, may be located within a suitable housing to afford more protection than that provided by the illustrated position, which is somewhat exposed.

Referring now to FIG. 3, the internal construction of the regulating valve according to the invention will be described. A suitably configured cap member 27 is secured to housing portion 24 by means of threaded fasteners 25. A seal is provided between the housing portion 24 of valve 22 and the wall of buoyancy sphere 15 by means of a suitable gasket 28. A flexible diaphragm 29 is positioned between cap member 27 and housing portion 24 and the entire assembly of housing portion 24 and cap member 27, gasket 28 and diaphragm 29 are held into a unitary assembly by means of threaded fasteners 25. If desired, other constructional arrangements may be employed rather than use threaded fasteners 25, for example, cap portion 27 may be integrally formed into buoyancy sphere 15 and housing portion 24 may be bodily threaded thereon. However, the illustrated arrangement permits independent servicing and replacement of the valve system.

As may be seen, diaphragm 29 divides the internal void between cap member 27 and housing portion 24 into two compartments. A suitably configured backing plate 31 is placed adjacent diaphragm 29 in the housing compartment and a similar backing plate 32 is placed on the other side of diaphragm 29 so as to be in the cap compartment. Besides performing their well understood function of stiffening diaphragm 29 so as to confine the flexure thereof to the outer circumference thereof, backing plate 32 provides an additional function of limiting the excursion of diaphragm 29 toward cap member 27. Backing plates 31 and 32 are held against diaphragm 29 so as to form a unitary construction therewith by means of a threaded stud 33 and suitable fasteners cooperating therewith.

A vent 34 is provided in cap member 27 so as to provide communication between the cap side of diaphragm 29 and the interior of buoyancy sphere 15. Similarly, a vent 35 provides access between the ambient water outside buoyancy sphere 15 and diaphragm 29 on the housing portion side thereof. As may be readily understood, the pressure differential between the interior of buoyancy sphere 15 and the ambient water surrounding it move diaphragm 29 either toward cap 27 or toward the housing portion 24 in dependence upon which pressure is the greater. It is for this reason that any protective cover surrounding valve 22 should have fluid access to the ambient fluid atmosphere surrounding buoyancy sphere 15.

Threaded shaft 33 on the end closest to valve body portion 23 supports a suitably configured pintle means 36. At the opposite end of pintle 36 a neck portion 37 positions a valve seal 38 against a valve seat 39 integrally formed with valve body portion 23. Neck portion 37 prevents pintle 36 from obstructing fluid flow when the valve seal 38 is raised off valve seat 39 in the well understood fashion. A fluid tight seal is made about pintle 36 by means of a gland 41 which may be thread-

edably received into valve body portion 23 or, if desired, simply retained by valve body portion 23 by means of a cooperating shoulder on valve housing portion 24. If desired, the fluid tight seal may be improved with the use of a suitable packing means such as O-ring 42 for example. Although providing a fluid tight seal, gland 41 and O-ring 42 permit pintle 36 to reciprocate and thereby follow the motion of diaphragm 29.

In the absence of pressure differential between the interior of buoyancy sphere 15 and the ambient surroundings, pintle 36 is biased so as to seat valve seal 38 on valve seat 39 by means of a biasing spring 43. Biasing spring 43 exerts its biasing force against a washer 44 which is held to pintle 36 by means of a suitable clip 45. The size and flexure of biasing spring 43 may be chosen so as to provide a predetermined bias on pintle 36 so as to correspond to a desired pressure differential at which the valve cracks open. In operative examples of the invention, a one pound per square inch differential between ambient sea pressure and internal buoyancy sphere pressure has been successfully maintained.

It will be observed that, in addition to vent 35, a plurality of vents 46 are provided in housing portion 24 of valve 22. Although these vents also provide pressure access from the ambient atmosphere to diaphragm 29, they serve another valuable and important function in the system of the invention. As previously noted, valve mechanisms used in the arduous surroundings of underwater marine engineering applications frequently suffer premature failures due to accumulations of mineral deposits and corrosive action of the seawater. Vents 46 effectively prevent this failure from occurring in the device of the invention by affording an exhaust vent permitting the valve of the invention to be flushed with fresh water after each use in a salt water environment. Thus, when the buoyancy transport vehicle 11 is taken aboard its service ship, a jet of fresh water may be introduced through vent 35 and flood the chamber formed between diaphragm 29 and actuator portion 24 and pass along the pintle 36 thereby cleansing spring 43 and exhausting through vents 46. This preventive maintenance permits the device to be deployed many times before valve 22 must be disassembled and inspected. This saving of operational time is of great importance when one considers the limited crew and working space aboard ocean vessels.

Although the foregoing description is sufficient for one skilled in the marine engineering arts to make and use the invention, the invention will be more readily understood with reference to the following mode of operation.

MODE OF OPERATION

The successful operation of the device provides automatic pressure equalization between buoyancy sphere 15 and the ambient environment during periods of descent. As buoyancy transport vehicle 11 is submerged beneath the surface of the water, the external pressure raises with relation to the interior of buoyancy sphere 15. When this pressure exceeds the interior pressure by the predetermined amount provided by biasing spring 43, the ambient pressure exerted on diaphragm 29 through vents 35 and 46 press diaphragm 29 inwardly. The excursion of diaphragm 29 is limited by the backing plate 32 contacting the wall of cap member 27. This limitation affords protection for diaphragm 29.

With diaphragm 29 in its innermost position, pintle 36 is drawn toward the interior of buoyancy sphere 15. This axial movement of pintle 36 raises valve seal 38 from valve seat 39. In this position, a fluid passage through the valve body portion 23 is established and suitable fuel flows from the lower pod fuel tank 19 through fluid conduit 21 to the gas generator, after which the gas is injected into the buoyancy sphere 15. Of course, the gas injected into the buoyancy sphere 15 raises the pressure therein until it equals the ambient pressure. When this condition has been obtained, biasing spring 43 restores pintle 36 to its outward position thereby forcing valve seal 38 against valve seat 39. In this position, the flow of fuel through the valve body is interrupted and the manufacture of gas within the gas generator ceases.

As a result of this regulatory action, a nearly uniform pressure differential is caused to exist between the interior of buoyancy sphere 15 and its ambient environment during periods of descent. This regulation provides the desired control and frees the diver-operator 12 to focus his attention and apply his efforts to other tasks.

The foregoing description taken together with the appended claims is seen to constitute a meritorious advance in the art which was unobvious to those skilled in the marine engineering and naval architecture arts not having the benefit of these teachings. Further, the device of the invention meets the aforesigned objects of invention and generally constitutes a meritorious advance in the arts.

Obviously, many modifications and variations of the present invention are possible in the light of the above teachings, and, it is therefore understood that within the scope of the disclosed inventive concept, the invention may be practiced otherwise than specifically described.

What is claimed is:

1. In a buoyancy transport vehicle having a buoyancy sphere for providing lifting buoyancy for objects attached to said vehicle, a buoyancy regulation system comprising:
a source of fuel under pressure;
a gas generator effectively joined to said buoyancy sphere for providing buoying gas therefor;
fluid conduit means connected between said source of fuel under pressure and said gas generator for providing a passage therebetween;
valve means effectively connected in said fluid conduit means for regulating the fuel flow through said fluid conduit means, said valve means including:
a valve housing connected to the buoyancy sphere and having a first passage effectively connecting the interior of the valve housing to the interior of the buoyancy sphere and a second passage means for connecting the valve housing to the ambient fluid surrounding the buoyancy sphere,
a flexible diaphragm within said valve housing and constructed to divide said valve housing into two compartments, one compartment being open to the interior of the buoyancy sphere via said first passage and the other compartment being open to the pressure of the ambient seawater environment via said second passage means;
a valve seat made integral with said valve housing and effectively connected to said fluid conduit means

and shaped to provide a passage orifice in fluid communication with said fluid conduit means; a pintle reciprocally mounted in said valve housing and formed to open and close the fluid passage provided by said valve seat and mechanically connected to said diaphragm to be reciprocally displaced thereby; and resilient means biasing said pintle to a closed or seated position with respect to said valve seat and yieldable to permit said pintle to assume an open position with respect to said valve seat upon the pressure in the ambient environment exceeding the force provided by the resilient biasing means and the pressure within said buoyant sphere. 10

2. A buoyancy regulation system according to claim 1 wherein said valve housing includes: 15

a regulator portion having an enlarged end configured to receive said flexible diaphragm in a hollow recess therein;

a cap portion fitting over the hollow recess of said regulator portion for retention thereon so as to close the end thereof and cooperate with said flexible diaphragm to form said one compartment therewith; and

a valve body portion attached to said regulator portion for receiving said fluid conduit means and containing said valve seat therein. 25

3. A buoyancy regulation system according to claim 2 in which said valve housing is attached to said buoyancy sphere with the cap portion and the enlarged end 30 of said regulator portion within said buoyancy sphere and the remainder of the regulator portion together with the valve body portion extending from said buoyancy sphere.

4. A buoyancy regulation system according to claim 3 further including:

a gasket positioned between the enlarged end of said regulator portion of said valve housing and the inner surface of buoyancy sphere for providing a high-pressure gas-tight seal therebetween; and fastening means cooperatively engaging said cap por- 35

tion, the enlarged end of said regulator portion, said gasket, and said buoyancy sphere and drawing said engaged elements together for ensuring a gas tight mechanical joint between said valve housing and said buoyancy sphere.

5. A buoyancy regulation system according to claim 4 further including:

a first backing plate secured to said flexible diaphragm on one side thereof so as to be within said one compartment which is open to the interior of said buoyancy chamber; and

a second backing plate secured to the other side of said flexible diaphragm opposite to said first backing plate, so that the flexure of said flexible diaphragm in response to pressure difference may be controlled within predetermined limits.

6. A buoyancy regulation system according to claim 5 wherein the backing plates have a thickness selected to cooperate with the interior of the aforesaid valve body means so as to limit flexure movement of the aforesaid flexible diaphragm.

7. A buoyancy regulation system according to claim 6 including:

threaded shaft means effectively attached to said pintle means and to said flexible diaphragm so as to extend through the regulator portion of said valve body for movement of said pintle means with said flexible diaphragm; and

valve seal means carried by said pintle means to cooperate with the aforesaid valve seat for opening and closing the fluid passage therethrough in response to movement of said flexible diaphragm.

8. A buoyancy system according to claim 7 in which said pintle has a smaller cross section in the vicinity of said valve seal means for facilitating the fluid flow.

9. A buoyancy system according to claim 1 including fluid passage vents in the regulator portion of said valve body communicating between the interior and exterior thereof to permit the washing of the interior of the valve with fresh water without disassembly of the valve. 40
